UNITED STATES PATENT OFFICE

148,391

DESIGN FOR A LAWN CHAIR

Ned Plourde and Frank Plourde, Gaastra, Mich.

Application April 17, 1946, Serial No. 128,686

Term of patent 7 years

(Cl. D15—1)

To all whom it may concern:

Be it known that we, Ned Plourde and Frank Plourde, citizens of the United States, residing at Gaastra, in the county of Iron and State of Michigan, have invented a new, original, and ornamental Design for a Lawn Chair, of which the following is a specification, reference being had to the accompanying drawing, forming part thereof.

Figure 1 is a perspective view of a lawn chair showing our new design.

Figure 2 is a fragmentary perspective view of the integral lattice, used in the back rest of the subject shown in Figure 1.

The dominant feature of the design resides in the appearance of the integrally latticed chair back, as shown.

We claim:

The ornamental design for a lawn chair, as shown and described.

NED PLOURDE.
FRANK PLOURDE.
